US00D726123S

(12) **United States Design Patent**
Su et al.

(10) **Patent No.:** US D726,123 S
(45) **Date of Patent:** ** Apr. 7, 2015

(54) **CIRCULAR CONNECTOR**

(71) Applicant: **Nextronics Engineering Corp.**, New Taipei (TW)

(72) Inventors: **Hou-An Su**, Keelung (TW); **Hai-Wen Yang**, Baoji (CN); **Xin-Chao Xiao**, Hunan Province (CN)

(73) Assignee: **Nextronics Engineering Corp.**, New Taipei (TW)

(**) Term: **14 Years**

(21) Appl. No.: **29/444,735**

(22) Filed: **Feb. 3, 2013**

(51) **LOC (10) Cl.** 13-03

(57) **CLAIM**

The ornamental design for a circular connector, as shown and described.

DESCRIPTION

FIG. 1 is a perspective view of a circular connector showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front view showing the practical usage thereof.

The dashed line lines shown in the drawings represent portions of the circular connector and environment that form no part of the claimed design.
